UNITED STATES PATENT OFFICE.

MACIEJ SWIDER, OF UTICA, NEW YORK.

GLOBE-MANIPULATOR.

1,366,296.

Specification of Letters Patent. Patented Jan. 18, 1921.

Application filed March 30, 1920. Serial No. 369,861.

To all whom it may concern:

Be it known that I, MACIEJ SWIDER, a citizen of Poland, residing at Utica, in the county of Oneida and State of New York, have invented certain new and useful Improvements in Globe-Manipulators, of which the following is a specification.

This invention relates to certain new and useful improvements in globe manipulators and is particularly designed so as to enable a person to readily place electric lamps in or remove the same from their sockets when situated quite a distance above the person without the necessity of employing ladders or the like.

The primary object of the present invention is to provide a globe manipulator of the above type composed of a plurality of sections arranged end to end and having detachably interlocked shaft sections operatively associated with a globe grasping member, means being provided in each section for driving the shaft section carried thereby so that any number of sections may be employed in accordance with the distance at which the lamp socket is situated above the operator.

Further objects will appear as the nature of the invention is better understood, and the same consists in the novel form, combination and arrangement of parts hereinafter more fully described, shown in the accompanying drawings and claimed.

In the drawings wherein like reference characters designate corresponding parts throughout the several views,

Figure 1 is a side elevational view of a globe manipulator constructed in accordance with the present invention and shown operatively engaging an electric lamp bulb fastened in a socket carried by a ceiling,

Fig. 2 is an enlarged vertical sectional view of one of the sections of the device shown in Fig. 1 together with adjacent end portions of adjacent sections.

Fig. 3 is a transverse sectional view taken substantially upon line III-III of Fig. 2,

Fig. 4 is a transverse sectional view taken substantially upon line IV-IV of Fig. 2,

Fig. 5 is an end view of one of the sections of the device shown in Fig. 1,

Fig. 6 is a view in elevation and partly broken away of the device shown in Fig. 2,

Fig. 7 is an elevational view looking toward the right of Fig. 6, and

Fig. 8 is a transverse sectional view taken

substantially upon line VIII-VIII of Fig. 6.

Referring more in detail to the several views, the present invention embodies a staff composed of a plurality of sections 5 arranged in end to end contacting relation and thus retained by means of suitable spring fasteners 6, the hooked ends 7 of said fasteners being detachably engaged in sockets 8 provided in the end portion of the section immediately above that to which said fasteners are secured.

Each staff section 5 is preferably of circular form in cross section and formed of two similar vertical members hinged along one side as at 9 to swing toward and away from each other and adapted to be fastened in closed or contacting relation by means of suitable latches 10 opposite the hinges 9.

Suitable bearings 11 and 12 are fastened to one member of each staff section 5, and these bearings support a rotatable shaft section 13 in each staff section. Upon the opposite ends of each shaft section 13 are fastened disks 14 having outer serrated faces of such form that when the sections are arranged in end to end relation as shown in Fig. 2, the disk 14 of one section will interlock with the disk of the adjacent section so that rotation may be imparted to all of the shaft sections simultaneously upon driving any one of the same. It is to be understood that one of the staff sections 5 will not have a disk 14 secured upon the upper end of the shaft section carried thereby, a suitable globe grasping member 15 being secured thereon instead.

Each staff section 5 is centrally chambered to accommodate a bevel gear 16 which is fastened upon the shaft section 13 thereof and which meshes with an adjacent bevel gear 17 carried upon a stub shaft 18 which extends through one of the members of said staff section and is squared as at 19 upon its outer end so as to receive a hand crank or the like for driving the stub shaft 18 and through gears 16 and 17 imparting rotation to the shaft section 13 as well as to the other shaft sections 13 connected therewith, and the globe grasping member 15.

From the above it will be understood that if the staff shown in Fig. 1 is not sufficiently long to enable an operator to reach a globe from the floor of a dwelling or the like, it is simply necessary to add another or other staff sections 5 to the lower end of the staff

shown, and when this is done, the hand crank 20 is of course removed from the lower stub shaft 18 of the device shown in Fig. 1 and placed upon the similar stub shaft of the lowermost one of the added staff sections. Similarly, if the staff shown in Fig. 1 is too long, any desired one or more of the sections 5 may be readily removed by simply springing the hooked ends 7 of the 10 fasteners 6 out of the sockets 8 of the lowermost section 5 which is to be retained, and the desired sections may be then removed. The hand crank 20 is of course then applied to the stub shaft 18 of the lowest staff section 5 which remains.

The staff sections 5 are formed in two longitudinal members which are hinged together and detachably connected in closed relation because of the fact that it may be 20 become necessary to repair the bearings 11 or 12 or other parts associated with the stub shafts 18 or shaft sections 13 from time to time.

From the foregoing description it is believed that the construction and operation 25 of the present invention will be readily understood.

Minor changes may be made without departing from the spirit and scope of the invention as claimed.

What I claim as new is:—

1. A globe manipulator of the class described comprising a plurality of staff sections each having a shaft section journaled 35 therein longitudinally thereof, means for detachably rigidly connecting said staff sections in end to end relation, means upon the ends of said shaft sections for clutching one to the other when the staff sections are connected, an operating member, means associated with each staff section to permit ap-

plication of power to the shaft section thereof whereby any desired one of the shaft sections may be driven by said operating member, and a globe grasping device fastened 45 upon one end of one of said shaft sections.

2. A globe manipulator of the class described comprising a plurality of staff sections each having a shaft section journaled therein longitudinally thereof, means for detachably rigidly connecting said staff sections in end to end relation, means upon the 50 ends of said shaft sections for clutching one to the other when the staff sections are connected, means to permit application of power to any one of said shaft sections, and a globe grasping device fastened upon one end of one of said shaft sections, each of said staff sections comprising a pair of hingedly connected longitudinal members having 55 means for locking the same in contiguous or closed relation whereby said members may be separated for gaining access to the shaft sections.

3. A globe manipulator comprising a staff 65 which embodies a plurality of sections, means to detachably connect said staff sections in end to end relation, a shaft section journaled longitudinally in each staff section and having means at its ends for clutching 70 the same to the shaft sections of adjacent staff sections when the latter are operatively connected thereto, means upon the outer end of one end staff section for grasping a globe, and means to permit application 75 of power to the shaft section of each staff section, said means comprising stub shafts rotatably geared to the shaft sections and having crank receiving outer ends.

In testimony whereof I affix my signature. 80

MACIEJ SWIDER.
